UNITED STATES PATENT OFFICE.

EMMETT W. OVERSTREET, OF MURRAY, UTAH.

INTERNAL-COMBUSTION ENGINE.

1,310,368.

Specification of Letters Patent. Patented July 15, 1919.

Application filed August 27, 1917. Serial No. 188,402.

To all whom it may concern:

Be it known that I, EMMETT W. OVERSTREET, a citizen of the United States, residing at Murray city, county of Salt Lake, 5 State of Utah, have invented certain new and useful Improvements in Internal-Combustion Engines, of which the following is a specification.

The present invention relates to internal 10 combustion engines, and has for an object to provide an improved structure of engine for increasing the power of the same without materially adding to the weight and size of the motor.

15 The invention further aims at the provision of an engine or motor of this type which is so constructed as to provide an increased number of working cylinder parts; means for affecting the simultaneous combustion of charges of fuel in the additional cylinder parts with the usual cylinders employed; to provide a novel and relatively simple valve structure of actuating all of the cylinder parts in predetermined timed 20 relation; and to provide a novel arrangement of combustion chambers and means for effecting simultaneous sparking in the respective chambers.

25 The above, and various other more or less 30 important objects of this invention will be in part apparent, and in part brought out in the following detailed disclosure of the present embodiment of this invention, the same being illustrated in the accompanying drawings, wherein:

Figure 1 is a side elevation, parts being broken away, of an internal combustion engine constructed according to the present invention.

40 Fig. 2 is a vertical transverse section taken through the engine, showing the double cylinder arrangement of the engine and the valve mechanism for controlling the inlet and exhaust therefrom.

45 Fig. 3 is a detail front elevation of the crank case and the valve operating connections mounted upon the forward end thereof.

Fig. 4 is a sectional view of the connection 50 between the crank shaft and the valve operating shaft.

Referring to these drawings, wherein like parts are designated by similar numerals of reference throughout the several views, 55 10 designates a crank case of substantially cylindrical form extending lengthwise of the

motor and having an upstanding contracted neck portion 11 with marginal attaching flanges at its upper end. Supported in the crank case 10 is a crank shaft 12 which may 60 have any desired number of crank portions and which is preferably supported upon an intermediate bearing 13 formed in the crank case when the latter is of any considerable length.

65

Mounted upon the crank case 10 are a plurality of lower cylinders 14, the latter having a head 15 closing its lower end and adapted to seat upon the neck 11 of the crank case. The upper end of the cylinder 14 is open and receives thereon the lower end of a corresponding upper cylinder 16. The lower end of the cylinder 14 has a laterally off-set head 17 immediately above the closure wall 15 while the cylinder 16 has 70 upon its lower end a laterally off-set head 18 communicating with the top of the cylinder 14 and arranged immediately beneath a closure wall 19 at the bottom of the cylinder 16. Preferably, the closure wall 19 and 75 the head 18 are cast or otherwise suitably formed with a connecting section 20 arranged between the cylinders 14 and 16, and which is provided with a laterally off-set head 21 arranged above the wall 19 and 80 communicating with the lower end of cylinder 16. A detachable laterally off-set head 22 is mounted upon and closes the upper end of the cylinder 16. Each cylinder is thus provided with a laterally off-set head at each 85 end and with a partition or closure wall 19 between the cylinders to prevent intercommunication between the same.

Water jackets 23 are preferably formed about the cylinders 14 and 16, and in the 90 closure walls 15 and 19, and in the top of the upper detachable head 22. Each laterally off-set head, is formed with intake and discharge ports 24 and 25, the latter preferably 95 extending in opposite upward and downward directions from the adjacent head and communicating with intake and exhaust manifolds 26 and 27. There are thus two manifolds for each head. The manifolds on the upper ends of the cylinders are preferably disposed upon one side of the engine, 100 and the manifolds on the lower ends of the cylinders are preferably disposed upon the opposite side of the engine. The cylinders are arranged in co-axial pairs, or in tandem, 105 and any desired number of pairs of cylinders 110 may be employed, and the lower cylinders

may be cast *en bloc* as shown, or may be arranged in any other suitable form desired. The upper cylinders 16 may also be likewise and correspondingly formed.

- 5 In each pair of cylinders 14 and 16 are disposed a pair of pistons 28 and 29, the same being connected in tandem by a common piston rod 30 extending longitudinally through the cylinders 14 and 16 and through 10 a stuffing box 31 mounted in the partition wall 19 to pack the piston rod 30 and prevent leakage of gas thereabout. The lower end of the piston rod 30 passes through a second stuffing box 32 mounted in the lower 15 closure wall 15, and is pivotally connected at its lower extremity to a connecting rod 33 which is mounted at its lower end upon the adjacent crank portion of the shaft 12.
- Each cylinder, 14 and 16 is provided in 20 its opposite ends with spark plugs 34 and 35 arranged oppositely to the adjacent heads of each cylinder, and a divided high tension lead 36 is connected at its ends to the spark plugs 34 at one side of the engine and at the 25 lower end of each cylinder, while a second high tension lead 37 is connected to the other spark plugs 35 at the opposite side of the engine and at the upper ends of the cylinders 14 and 16. With this arrangement combustion takes place simultaneously in the 30 upper ends of both of the cylinders, and at a spaced period of time in the lower ends of the cylinders.

Each port, 24 and 25 is provided with a 35 controlling valve 38 mounted upon a stem 39 projecting downwardly from the adjacent off-set head and held to its seat by a spring 40 surrounding the stem and adjustably engaging against the lower side of the 40 head by pressure of an adjusting nut 41 mounted upon the valve stem 39. The lower end of the valve stem is mounted in a guide 42 in the form of a bracket arm projecting from the adjacent side of the engine and being vertically apertured to receive the valve 45 stem 39 therethrough. The lower extremity of the valve stem is forked to receive an anti-friction roller 43, and the valve stems are arranged in upper and lower longitudinal 50 rows at the opposite sides of the engine. Beneath each row of valve stems is a cam shaft 44, the same being journaled in suitable brackets 45 projecting from the adjacent side of the engine and having thereon 55 a plurality of cams or lobes 46 arranged at suitable relative angles axially of the cam shaft 44 and adapted to engage the rollers 43 for lifting the valves 38 at predetermined times.

60 At preferably the forward end of the engine and at opposite sides thereof, is arranged a pair of vertically extending operating shafts 47 provided with bevel gears 48 meshing with corresponding bevel gears 49 fixed to the adjacent cam shafts 44. The

lower ends of the operating shafts 47 have bevel gears 50 thereon which mesh with bevel gears 51 mounted on stub shafts 52 projecting from the forward end of the crank case 10, by means of brackets 53. The 70 stub shafts 52 are also secured to spur gear wheels 54 which mesh with a driving pinion 55 mounted upon the crank shaft 12 and arranged in the plane of and between the gear wheels 54.

75 It will be noted from Fig. 2 particularly that the valve stems 39 on the side of the engine where the off-set heads are on the lower ends of the cylinders, project upwardly from the heads for the purpose of 80 compactness in structure and for facilitating access to the cams and their adjacent parts.

Any suitable ignition system may be used in conjunction with the engine of this invention, and where four pairs of cylinders 85 are employed, as shown, an eight cylinder commutator will be required for operating the superposed pistons in tandem and effecting impact upon the pistons in both their upward and downward movements.

90 It is of course understood that various changes and modifications may be made in the details of construction and design of the engine of this invention without departing from the spirit thereof, the changes and 95 modifications being restricted only by the scope of the following claims:

I claim:

1. In an internal combustion engine, the combination of a pair of cylinders arranged in tandem, connected pistons therein, a laterally off-set head on the lower end of the lower cylinder, a detachable laterally off-set head closing the upper end of the upper cylinder, a connecting member arranged between the cylinders having a partition wall separating the same and provided with off-set heads at opposite sides of the partition wall communicating respectively with the lower end of the upper cylinder and the upper end of the lower cylinder.

100 2. In an internal combustion engine, the combination of a pair of cylinders arranged in tandem, connected pistons mounted in the cylinders, a crank shaft, a connection between the crank shaft and the pistons, controlling valves at the opposite ends of the cylinders, cam shafts for the controlling valves for actuating the same, operating shafts connected to the cam shafts and having bevel gears upon their lower ends, a stub shaft arranged below each operating shaft and having bevel gear thereon meshing with the gear of the adjacent operating shaft, spur gears mounted on the stub shaft, a pinion mounted on the crank shaft between the spur gears for actuating the same, and a crank case supporting said crank and stub shafts.

115 3. In an internal combustion engine, the

- combination of a plurality of lower cylinders, a plurality of upper cylinders arranged in tandem relation with the lower cylinders, inlet and exhaust valves connected to the opposite ends of said upper and lower cylinders and arranged in longitudinal rows at the opposite sides of the engine, cam shafts extending longitudinally at the opposite sides of the engine for operating the valves in predetermined timed relation, operating shafts arranged vertically at each side of the engine and having connection with the respective cam shafts, a crank shaft, connected pistons in each superposed pair of cylinders having connection with the crank shaft, and connections between the crank shaft and said operating shafts.
4. In an internal combustion engine, the combination of superposed rows of cylinders arranged in tandem, pairs of exhaust and intake manifolds extending laterally across the upper and lower ends and at the opposite sides of the cylinders, valves at the opposite ends of the cylinders and at opposite sides thereof for controlling the exhaust and intake to the opposite ends of the cylinders, cam shafts at the opposite sides of the engine between the pairs of manifolds for actuating the valves, a crank case connected to the lower cylinders, a crank shaft in the crank case, connected pistons in the superposed cylinders having connection with the crank shaft, vertical operating shafts at the opposite sides of the engine having connection with the respective cam shafts, and connections between the operating shafts and the cam shaft for driving the former.
5. In an internal combustion engine, the combination, of a pair of cylinders arranged in tandem, connected pistons therein, a laterally off-set head on the lower end of the lower cylinder, a detachable laterally off-set head closing the upper end of the upper cylinder, a connecting member arranged between said cylinders having a partition wall separating the same and provided with offset heads at opposite sides of the partition wall communicating respectively with the lower end of the upper cylinder and the upper end of the lower cylinder, the lateral off-set heads in said upper and lower heads extending on opposite sides of the cylinder, controlling valves in said heads, a crank shaft, and means operated by said crank
- shaft to operate said valve in the lateral off-set on the same sides of the cylinders in unison and at intervals to the operation of the valve in the off-set on the opposite sides of the cylinders.
6. In an internal combustion engine, the combination, of a pair of cylinders arranged in tandem, connected pistons therein, a laterally off-set head on the lower end of the lower cylinder, a detachable laterally off-set head closing the upper end of the upper cylinder, a connection member arranged between said cylinders having a partition wall separating the same and provided with offset heads at opposite sides of the partition wall communicating respectively with the lower end of the upper cylinder and the upper end of the lower cylinder, the off-set of said upper and lower heads extending on opposite sides of the cylinder, controlling valves in said heads, means for simultaneously operating the valve in the off-set portion on the same side of the cylinder, to admit a charge to the upper end of the cylinder, means for operating the valves on the opposite sides of the cylinders to admit a charge to the lower end of the cylinder at a spaced interval of time from the admission of the first charge, and means for simultaneously igniting the charges in the upper end of the cylinder and at a spaced interval of time, the charges in the lower end of the cylinder.
7. In an internal combustion engine, the combination of a pair of cylinders arranged in tandem, connected pistons therein, a laterally off-set head on the lower end of the lower cylinder, a detachable laterally off-set head closing the upper end of the upper cylinder, a connection member arranged between said cylinders having a partition wall separating the same and provided with offset heads at opposite sides of the partition wall communicating respectively with the lower end of the upper cylinder and the upper end of the lower cylinder, inlet and exhaust ports communicating with each of said off-set heads, inlet control valves carried by said heads, and means for simultaneously operating certain of said valves and means for simultaneously operating at a spaced interval of time the remaining valves.

EMMETT W. OVERSTREET.
